UNITED STATES PATENT OFFICE

2,524,158

COMBUSTION HEATER

Theodore S. Briskin, Santa Monica, Calif., assignor to Excel Auto Radiator Company, Chicago, Ill., a corporation of Delaware

Original application December 21, 1942, Serial No. 469,668. Divided and this application May 11, 1948, Serial No. 26,420

3 Claims. (Cl. 126—91)

1

This invention relates to improvements in combustion heaters of a type particularly adapted for use in automobiles or airplanes.

Combustion heaters of this type are generally provided with a sealed combustion chamber in communication with the intake manifold of an internal combustion engine. A mixture of gasoline and air is drawn into the combustion chamber and is there ignited. The combustion chamber is generally provided with radiator fins and a blower to effect proper heat exchange.

The outstanding characteristic of a heater of this type is that a great amount of heat can be generated in a very compact unit. This is accomplished in part by the use of a readily volatilizable fuel such as gasoline so as to facilitate complete combustion, and in part by causing the combustible mixture and products of combustion to flow through the heater at a rapid rate, thereby causing a greater rate of combustion than would normally occur in a heater of comparable size. The term "combustion heater" as hereinafter used refers specifically to a heater of the type having the above mentioned characteristics, as compared with the usual type of fuel burning apparatus.

The preferred embodiment of the invention herein shown and described is of a type adapted for use in automobiles or airplanes, but it is understood that this invention is not limited to use in connection with a vehicle operated with an internal combustion engine. A combustion heater embodying this invention is equally adaptable for use in other applications where the requisite pressure difference between the intake and exhaust can be supplied.

The efficiency of a combustion heater is limited however by two considerations: the type of heat exchange or heat dissipating means provided and the completeness of the combustion. The heat generated must be dissipated, not only to prevent overheating and damage to the heater, but to be useful, the heat must be dissipated by the heat exchange means provided in order that it may not pass out through the exhaust in the form of high temperature products of combustion. On the other hand, the temperature of the combustion zone must be maintained sufficiently high as to insure complete combustion.

It has been the practice in the prior art to provide a chamber in which the combustion is caused to take place, the walls of this chamber constituting the heat exchange means. As the efficiency of this heat exchange means is increased, as by the provision of radiator fins, a blower, and other structural improvements, the temperature of the combustion chamber is lowered, thereby increasing the amount of carbon monoxide in the flue gas and reducing the overall efficiency of the heater. As a practical matter, it

2

is difficult to achieve the correct balance between heat exchange capacity and the proper temperature of the combustion chamber, with the result that complete combustion is attained only in combination with insufficient heat exchange capacity or inefficient heat exchange means. A large portion of the heat is thereby wasted. In other words, where the wall of the combustion chamber forms a part of the heat exchange means, the result is inefficient operation, the flue gas either being of excessive temperature, or else containing an unduly large proportion of carbon monoxide.

In the present invention, the wall of the combustion chamber does not constitute a portion of the heat exchange means. A manifold chamber is provided for the products of combustion, and the combustion chamber is disposed within the manifold chamber, and spaced from the walls thereof so that the combustion chamber is surrounded by the hot products of combustion. The temperature difference on either side of the wall of the combustion chamber being comparatively small, a high temperature may be maintained within the combustion chamber which will result in substantially complete combustion of the fuel and its dissociation products.

It is a further object of this invention to provide an improved arrangement of parts within the manifold chamber, such as the arrangement of the baffles, and the arrangement of the combustion chamber, and an outlet conduit, so that the products of combustion are caused to circulate along the entire periphery of the side walls of the manifold chamber before being finally educed, thus effecting a maximum heat exchange. In this connection it will be further noted that the design of the manifold chamber herein disclosed is such that it can be die cast in integral form, with the exception of one side wall. The remaining parts are so designed that they are independently mounted with respect to the die casting, thus providing a minimum of joints through which gas may escape.

Various other objects, features and advantages will become apparent as the description proceeds.

Reference is hereby made to the accompanying drawings which form a part of this specification, and in which a preferred embodiment of this invention is illustrated, like reference numerals referring to like parts:

Fig. 1 is a plan section of a preferred embodiment of this invention;

Fig. 2 is an end view of the heater shown in Fig. 1, the gasoline mixing chamber being shown in section; and

Fig. 3 is a section taken along line 3—3 of Fig. 1.

With reference now to Figs. 1 and 2, the heater 60 comprises a housing 10 surrounding the four

sides of the heater. A motor 12 is positioned above the housing 10 and is mounted by means of motor brackets 13 which, as shown in Fig. 2, may be secured to the housing by any suitable means, such as by a screw and a spacer. A fan, not shown, is driven by the motor, the fan being positioned in the upper portion of the housing 10 and above a plurality of fins 15 which are enclosed by the housing.

A manifold chamber 16 is disposed within the housing, the fins being mounted on the manifold chamber and being held in spaced relation with each other by any suitable means, such as by welding the fins to the walls of the manifold chamber. The manifold chamber is provided with a flange 17 into which a plurality of studs 18 are threaded whereby the manifold chamber may be secured.

A plate 19 having two cylindrical bosses 20 and 21 cast integrally therewith is positioned adjacent the housing 10 at a point opposite the manifold chamber 16. A heat resistant gasket 22 is interposed between the plate 19 and the side wall of the housing, and a similar heat resistant gasket 23 is positioned between the manifold chamber and the side wall of the housing, the studs 18 passing through the plate 19, the gaskets 22 and 23, and the side wall of the housing 10, so that the whole assembly may be rigidly secured together.

The boss 20 is drilled to receive an inlet tube 24 which extends into a larger cavity formed within the boss which cavity may be referred to as the ignition chamber 25. A heat resistant cup-shaped member 26, the closed end of which is perforated so as to provide a baffle 27, is fitted into the ignition chamber. Discs 28 and 29 of refractory material are positioned adjacent the open end of the cup-shaped member 26, the disc 28 being perforated at its central portion and being undercut peripherally thereof to form an annular chamber as indicated at 30, and the disc 29 being provided with a plurality of peripherally arranged perforations 31 to form passageways communicating with the chamber 30. The bore in the boss 20 is threaded as indicated at 32, and a closed tube 33 is threaded into the boss and confines the cup-shaped member 26 and the discs 28 and 29 in position. The closed tube 33 forms a combustion chamber 35, the remote end of the tube being provided with a slot 34 through which burning gases may escape from the combustion chamber.

The boss 21 is drilled to provide an outlet passage 36, a portion of the boss being internally threaded as indicated at 37, and a closed tube 38 being screwed into the boss so as to form a continuation of the outlet passageway 36. A slot 39 is formed in the closed tube 38, the slot running substantially the full length of the tube.

The manifold chamber 16 is preferably die cast in a single piece having an end wall 40 and walls 41, 42, 44, and 46 which can be referred to generically as side walls. The interior of the manifold chamber is divided into three communicating compartments by a baffle 43 which extends downwardly from the upper side wall 44 and a baffle 45 which extends upwardly from the lower side wall 46. The upper and lower walls are curved as shown in Fig. 3.

When the manifold chamber 16 and the assembly, comprising plate 19 and its associated parts described above, are secured together by means of the studs 18, it will be noted that the closed tube 33 is received in one of the compartments

of the manifold chamber and the outlet tube 38 is received in another compartment, as shown in Fig. 3. The flow of gas from the tube 33 to the outlet tube 38, as shown by arrows in Figs. 1 and 3, is caused to follow the side walls of the manifold chamber 16 due to the arrangement of the baffles 43 and 45. This permits a maximum amount of heat exchange with the walls of the manifold chamber and the manifold chamber causes the maximum heat available to be extracted from the products of combustion before they are finally educed from the manifold chamber. It will be noted that the tubes 33 and 38 are independently and rigidly mounted with respect to the manifold chamber 16, with their closed ends abutting against the end wall 40 of the manifold chamber.

A tubular member 50 is disposed above the inlet boss 20, as shown in Fig. 2, and is provided with two arms 51 and 53. The arm 51 is drilled to provide a mixing chamber 52 at the lower portion thereof, and the arm 53 terminates in a clamp 54 which is secured to the outlet boss 21, as shown in Fig. 2. By means of this clamp, the tubular member 50 and its associated parts are mounted with respect to the other portions of the heater.

The mixing chamber 52 is provided with a liner 55 which is in the form of a Venturi tube. The upper portion of the arm 51 is drilled to provide a gasoline passageway 57, and a gasoline supply tube 56 is positioned in the passageway and extends downwardly to the constricted portion of the Venturi tube. A plurality of laterally disposed air inlets 58 are formed in the arm 51 at the upper portion of the mixing chamber. It will be seen that the parts just described function in the usual manner to carburet the gasoline which is fed into the ignition chamber 25.

A gasoline supply line may be suitably connected to gasoline passageway 57, through a suitable control valve. A plug 62 closes the lower end of the mixing chamber and holds the liner 55 in place. A passageway 66 provides communication between the mixing chamber 52 and the inlet tube 24. The lower portion of the arm 51 is secured to the end surface of the boss 20 by means of screws 64, and a heat resistant gasket 63 is interposed between the two members.

A spark plug 65 is mounted in the wall of the ignition chamber 25 so that the carburetted gasoline which is drawn into the ignition chamber may be ignited. The burning mixture then passes through the passageways in the discs 28 and 29 and further combustion takes place in the combustion chamber 35. The hot gases then pass through the outlet passageway 36 and through a conduit 67 into the intake manifold of the gasoline engine. The conduit 67 is screw-threaded into the end of the boss 21, as shown in Fig. 1. After combustion continues for a short period of time, the refractory discs 28 and 29 become heated to the state of incandescence so that the ignition provided by the spark plug 65 is no longer needed. Suitable means may be provided for breaking the circuit to the spark plug when this state has been attained. It will be noted in this connection that the combustible mixture in passing from the ignition chamber 25 into the combustion chamber 35 is exposed to heat radiated from all directions due to the undercut construction of the discs 28 and 29, and all the heat so radiated is absorbed by the combustible mixture. Furthermore, any unvaporized droplets of gasoline, having a greater inertia than the vapor, will impinge upon the central portion of the disc 29

and will be vaporized before passing through the perforations 31 into the combustion chamber. The construction herein illustrated has been found to form a highly efficient means of ignition.

In operation, when the heater is initially turned on, ignition is effected by the spark plug 65. Thus, a partial combustion of the mixture will occur in the ignition chamber 25 which heats the refractory discs 28 and 29. After the discs have been heated to an incandescent state, the spark plug circuit is automatically opened, and the mixture thereafter is ignited as it passes through the refractory discs 28 and 29.

The provision of the tube 33 separates the zones of combustion and heat exchange, with the result that the wall of the combustion chamber 35 is maintained at a high temperature which promotes complete combustion of the fuel. The arrangement of the manifold chamber 16, as pointed out above, is such that the products of combustion are caused to follow the side walls of the manifold chamber throughout its complete periphery, and the flow stream of these products spreads out fanwise as it approaches the slot 39 in the outlet tube 38. Thus the maximum amount of heat exchange through the side walls of the combustion chamber is permitted to take place.

This application is a division of my copending application, Serial No. 469,668, filed December 21, 1942, now Patent No. 2,457,862, granted January 4, 1949, and the subject matter thereof, insofar as it is consistent with this application, is hereby incorporated by reference into this application.

Although only a preferred modification of this invention has been shown and described herein, it will be understood that various modifications and changes may be made therein without departing from the spirit of this invention. It is understood that the foregoing is intended to be illustrative only, and that this invention is to be limited only by the following claims.

I claim:

1. A heater of the combustion type comprising a plate having a tube rigidly mounted on said plate and extending from one side thereof, means secured to said plate in gas tight relationship and providing a chamber, said tube extending into said chamber and being completely surrounded thereby and being provided with means forming an outlet in the side wall of said tube for communication with said chamber, and being spaced from the side walls of said chamber, means forming an outlet for said chamber, refractory means disposed at the inlet of said tube to ignite a gaseous fuel as it flows into said tube so as to cause the combustion thereof as it passes longitudinally through said tube, and longitudinally arranged baffle means disposed between said tube and said chamber outlet forming means and extending inwardly from a side wall of said chamber to cause the products of said combustion to circulate outwardly from and in a peripheral direction, with respect to said tube, in the space between said tube and the side walls of said chamber before passing out of said chamber to said outlet, and heat exchange means operatively associated with the external surface of the side walls of said chamber.

2. In a heater of the combustion type, means forming an elongate manifold chamber having an end wall and side walls, a plurality of baffles longitudinally disposed within said chamber divid-

ing the same into a plurality of communicating compartments including a first compartment, a last compartment and an intermediate compartment, tubular means forming a combustion chamber mounted on said end wall and extending into said first compartment, means forming an outlet in the side wall of said tubular means for communication with said first compartment, and means forming an outlet for said last compartment, each of said baffles extending from one side wall of said manifold chamber toward an opposite side wall, but terminating short of the latter to provide communicating means between adjacent compartments, adjacent baffles extending from opposite walls so that the products of combustion pass out of said combustion chamber into said first compartment and through said other communicating compartments and into said outlet, said combustion chamber being spaced from the side walls of said manifold chamber, whereby matter surrounding said manifold chamber is heated by heat exchange with said products of combustion through the side walls of said manifold chamber and the temperature within said combustion chamber is maintained at a sufficiently high degree as to insure substantially complete combustion within said combustion chamber.

3. In a heater of the combustion type, means forming an elongate manifold chamber having an end wall and side walls, a plurality of baffles longitudinally disposed within said chamber dividing the same into a plurality of longitudinally disposed communicating compartments including a first compartment, a last compartment, and an intermediate compartment, tubular means forming a combustion chamber mounted on said end wall and extending into said first compartment, means forming an outlet in the side wall of said tubular means for communication with said first compartment, an outlet conduit mounted on said end wall and extending into said last compartment, each of said baffles extending from one side wall toward an opposite side wall and terminating short of the latter to provide communicating means between adjacent compartments, adjacent baffles extending from opposite walls so that as the products of combustion pass from said first-mentioned compartment through said other communicating compartments and into said outlet conduit the flow stream of said products of combustion will contact the side walls of said manifold chamber along the entire periphery thereof, and a longitudinal slot in the wall of said outlet conduit of a length approximating the length of the compartment in which said conduit is disposed to cause said flow stream to broaden out so as to increase the area of contact between said flow stream and said side walls, thereby increasing the heat exchange through said side walls.

THEODORE S. BRISKIN.
